UNITED STATES PATENT OFFICE.

RENE DANIEL GROVE, OF MIDDLETOWN, PENNSYLVANIA.

DESIGN FOR A TOY DUCK.

Application filed March 30, 1925. Serial No. 12,955. Term of patent 7 years.

To all whom it may concern:

Be it known that I, RENE DANIEL GROVE, a citizen of the United States, residing at Middletown, county of Dauphin, and State of Pennsylvania, have invented a new, original, and ornamental Design for a Toy Duck, of which the following is a specification, reference being had to the accompanying drawing, forming part thereof.

I claim:

The ornamental design for a toy duck as shown.

RENE DANIEL GROVE.
